UNITED STATES PATENT OFFICE.

LUCIUS DYER, OF MILLBRIDGE, MAINE, ASSIGNOR OF TWO-THIRDS TO
CHARLES H. DYER AND GEORGE S. SAWYER, BOTH OF SAME PLACE.

ANTI-FRICTIONAL CHOCK OR LEADER FOR RIGGING OF VESSELS.

SPECIFICATION forming part of Letters Patent No. 341,838, dated May 11, 1886.

Application filed January 4, 1886. Serial No. 187,509. (No model.)

To all whom it may concern:

Be it known that I, LUCIUS DYER, a citizen of the United States, and a resident of Millbridge, in the county of Washington and State 5 of Maine, have invented certain new and useful Improvements in Anti-Frictional Chocks or Leaders for the Rigging of Vessels; and I do hereby declare that the following is a full, clear, and exact description of the invention, 10 which will enable others skilled in the art to which it appertains to make and use the same, reference being had to the accompanying drawings, which form a part of this specification, and in which—

15 Figure 1 is a perspective view of a portion of a yard-arm provided with my improvement. Fig. 2 is a longitudinal sectional view of the same, and Fig. 3 is a perspective view, on an enlarged scale, of the bail and plate comprising my improvement.

Similar letters of reference indicate corresponding parts in all the figures.

My invention has relation to sheaves for the passage of a rope or sheet through a yard-arm, 25 spar, boom, or similar object; and it consists in the improved construction and combination of parts of a guide-bail for such a sheave, which will guide the sheet or rope straight to the sheave, preventing it from becoming 30 jammed at the side of the sheave in the slot, if the rope or sheet is drawn to one side or the other, thus insuring the free passage of the rope or sheet over the pulley, as herein-after more fully described and claimed.

35 In the accompanying drawings, the letter A indicates the end of a yard-arm, and this yard-arm is provided with the usual slot, B, having the pulley C, over which the sheet D passes, journaled within it. The upper end 40 of the slot is provided with a plate, E, which surrounds the slot, and is formed with a downwardly-projecting flange, F, which fits against the sides of the slot, filling out or lining the upper end of the slot. The plate is provided 45 near the outer end with two pairs of upwardly-projecting perforated lips, G G, one pair at each side of the slot, and the bail H, having its outer end bent at a right angle to its side pieces, has its ends pivoted upon boits 50 I I, passing through the perforated lips and through the ends of the bail. A rectangular

frame, J, is pivoted with pins K K, projecting from the middles of its end pieces, between the sides of the outer portion of the bail, and this frame is provided with two rollers, L L, which are journaled in the sides of the frame, having a space between them sufficient to allow the sheet to pass between them. 55

It will be seen that any strain from the sail upon the sheet will tilt the pivoted bail and 60 the rocking frame within the bail, so as to keep the sheet straight with relation to the sheave, so that the sheet may be hauled home, or may be slackened without any danger of the sheet chafing or getting caught in the slot 65 by being drawn toward the side of the slot away from the sheave, as will happen where no bail and guide-rollers are provided, the bail and rollers preventing any danger of the sheet breaking from being cut or chafed, and having 70 an undue strain exerted upon it. The plate surrounding the upper end of the slot will re-enforce this slot and prevent the strain of the sheet upon the sheave from splitting the yard-arm, the flange lining the entire top of 75 the slot and bearing considerable of the strain upon the slot. It follows that this guide-bail and rollers may be used in spars, booms, or any place where a rope passes over a sheave, and is liable to have a strain exerted upon it 80 transverse to the plane of the sheave, the device being applicable to any sheave which is journaled within a slot or recess in a rigid object, and not in a swiveled or freely-moving block. 85

It is obvious that the application of this improvement is not limited to the yard-arms of vessels, but that it may be employed with equal advantage as outfalls on booms of fore-and-aft vessels. 90

Having thus described my invention, I claim and desire to secure by Letters Patent of the United States—

1. In combination with a sheave journaled in a slot, a flanged plate lining the upper end 95 of the slot, and a pivoted frame above the sheave, having guide-rollers for the passage of a sheet, as and for the purpose shown and set forth.

2. In combination with a sheave journaled 100 in a slot, a pivoted frame above the sheave, having guide-rollers in its outer end, forming

a passage for a sheet or rope, as and for the purpose shown and set forth.

3. In combination with a sheave journaled in a slot, a bail having its outer end bent at a right angle to its arms and pivoted at the top of the slot with the ends of the arms, and guide-rollers journaled in the outer bent portion of the bail, as and for the purpose shown and set forth.

10 4. In combination with a sheave journaled in a slot, a bail having its outer end bent outward at a right angle to its arms, and having the ends of its arms pivoted near the outer end of the slot, a frame having its ends piv-

15 oted between the bent portion of the bail, and guide-rollers journaled in the pivoted frame, as and for the purpose shown and set forth.

5. In combination with a sheave journaled in a slot, a plate having a downwardly-pro-

jecting flange and lining the upper end and 20 the edges of the slot, and provided with two pairs of upwardly-projecting lips, a bail having its outer end bent at a right angle to its arms, and having the ends of the arms pivoted between the lips, a rectangular frame having 25 trunnions at its ends pivoted in the sides of the bent portion of the bail, and two guide-rollers journaled in the sides of the pivoted frame, forming a passage for a sheet or rope, as and for the purpose shown and set forth. 30

In testimony that I claim the foregoing as my own I have hereunto affixed my signature in presence of two witnesses.

LUCIUS DYER.

Witnesses:

EZEKIEL DYER,
HANNIBAL HAYFORD.
